ATTORNEY.

UNITED STATES PATENT OFFICE.

CHARLES LEO FITZ, OF FOND DU LAC, WISCONSIN, ASSIGNOR TO DROP HEAD PROJECTOR COMPANY, OF FOND DU LAC, WISCONSIN, A CORPORATION OF WISCONSIN.

SAFETY MECHANISM FOR OPTICAL PROJECTION MACHINES.

Application filed November 18, 1922, Serial No. 601,751. Renewed May 29, 1926.

This invention relates to means for preventing the spread of fire from within the usual encased motion picture machine when the picture film takes fire accidentally during 5 use of the machine in a picture projection operation.

The present improvement has for its object:—

To provide a structural formation and 10 combination of parts and elements constituting an automatic mechanism, interconnected with the enclosing housing and the entry door or doors of a motion picture machine, by means of which the electric circuit supplying electro-motive force to the electric 15 lamp used as an illuminant in the machine, is placed in an open or interrupted condition while the housing door or doors are in their opened condition, with such circuit automatically returned to and maintained in a 20 closed condition, with the closing and latching of said door or doors, all as will hereinafter more fully appear.

In the accompanying drawing:—

25 Fig. 1 is a side elevation of an enclosed motion picture machine illustrating the application of the invention.

Fig. 2 is a front elevation of the same.

30 Fig. 3 is an enlarged detail transverse section on line 3—3, Fig. 1, showing the preferred construction and arrangement of the combined latching and circuit controlling mechanisms of the invention.

35 Fig. 4 is a detail side elevation of the stationary portion of the mechanism on line 4—4, Fig. 3, with the strike or latch plate removed.

Fig. 5 is a face view of the strike or latch plate.

40 Fig. 6 is an elevation of the operating knob of the mechanism.

Fig. 7 is a detached side elevation of the engaging end of the movable portion of the mechanism.

45 Fig. 8 is an end elevation of the same.

Fig. 9 is a diagram showing the light circuit and switches of the system.

Like reference numerals indicate like parts in the several views.

50 Referring to the drawing, 1, designates a portion of the skeleton supporting frame or structure to which the central stationary enclosing shell 2 of the motion picture machine housing is attached, an example of which is described in detail in a prior appli-

cation, Serial No. 598,868, filed Nov. 3, 1922.

3 designates the side doors of the housing, hinged at their rear ends to the shell 2, in order to afford ready access to the interior of the housing from its respective sides. 60

4 designates counterpart rectangular extensions fixed on the skeleton frame 1 near its forward end and adapted to support the stationary portion of the combined latching and circuit controlling mechanism, now to 65 be described.

5 designates a bearing bracket attached to the extension 4 and provided with bearings for a shaft 6, carrying the semi-rotary bar shaped member 7 of a circuit closer. 70

8 and 9 designate a pair of contact fingers mounted in insulated relation on the extension 4, in the path of the semi-rotary member 7, and arranged in the hereinafter described electric circuit of the lighting 75 system of the machine.

10 designates a hub fixedly secured to the forward end of the shaft 6, with its forward end, in turn, formed with a diametric transverse groove 11 adapted for operative engagement with the hereinafter described tongue of the movable portion of the latch mechanism. 80

12 designates a strike or latch plate fixed on the extension 4 and formed with a slit 85 13 in aligned relation with the groove 11 of the hub 10, and adapted to permit the entry of the tongue above referred to.

14 designates a semi-rotary hub, forming the main member of the movable portion 90 of the latching mechanism. Said hub is journaled in an individual side door 3 of the machine housing, and carries at its outer end an operating handle 15, which in the construction shown is formed with a diametric groove 16 across its face which when filled with a material of contrasting color, is adapted to visibly indicate to the operator the condition of the latch mechanism. 95

17 designates the operating tongue above 100 referred to, of a plate form, and fixedly attached to the inner end of the hub 14, in longitudinal alignment with the shaft 6, and hub 10 aforesaid. In the present improvement the inner end of the tongue 17 is 105 formed with a pair of transversely projecting lugs 18, which in a movement of the mechanism to a closed position passes through the slit 13 of the latch plate 12, so that by a quarter turn of the knob 15 by 110

the operator, said lugs 18 are turned cross-wise of the slit 13 to lock the two portions of the mechanism together with the door in the required closed condition. In such turning 5 movement of the knob 15, the latch tongue 17, through its engagement with the hub 10 aforesaid, imparts a simultaneous rotation to the switch member 7 to establish an electric circuit between the contact fingers 10 or terminals 7 and 8, of the circuit closure mechanism individual to said individual latching mechanism.

As illustrated in Fig. 9, a separate latching and circuit closing mechanism is provided for each door 3 of the machine housing, with the terminals of the circuit closing portions of the mechanisms arranged in series in the circuit of the lamp 19 used for illumination, so that all the doors must 15 be closed and latched before current can pass to said lamp, and thus the main purpose of the invention is attained, to-wit:— 20 the prevention of the operation of the machine until all the doors are closed and latched and in order that on an accidental firing of the inflammable picture film, the fire will be confined wholly within the machine casing, which is necessarily formed 25 of metal or like non-fusible material.

Having thus fully described my invention what I claim as new and desire to secure by Letters Patent, is:—

1. In a safety mechanism for use with the electrical illuminating means of enclosed 35 optical projection apparatus, the combination of an enclosing housing provided with an entry door, a latching head mounted for turning adjustment in the door of a housing, a latch tongue fixed to an end of said 40 head, a revoluble circuit closing mechanism fixedly secured in the interior of said housing in aligned relation to said latch tongue and adapted for connection in an electric 45 circuit, and a keeper plate associated with said circuit closing mechanism and having latching engagement with the latch tongue aforesaid.

2. In a safety mechanism for use with the electrical illuminating means of enclosed 50 optical projection apparatus, the combination of an enclosing housing provided with

entry doors in its side walls, a plurality of latching heads mounted for independent turning adjustment in the plurality of doors of a housing, latch tongues fixed to ends of 55 said latching heads, a plurality of circuit closing mechanisms individual to the latching heads and fixedly secured in the interior of the housing in aligned relation to said latch tongue, said circuit closing mechanism 60 being connected in series in an electric circuit and formed with means for operative engagement with the latch tongues aforesaid, and keeper plates associated with said circuit closing mechanisms and formed for 65 latching engagement with the latch tongues aforesaid.

3. In a safety mechanism for use with the electrical illuminating means of enclosed optical projection apparatus, the combination 70 of an enclosing housing provided with an entry door, a latching head mounted for turning adjustment in the door of a housing, a latch tongue fixed to one end of said latching head and having lateral end projections, a revoluble circuit closing mechanism fixedly attached in the interior of the housing in aligned relation to said latch tongue and adapted for connection in an electric circuit, and a keeper plate associated 75 with said circuit closing mechanism and having a transverse slit adapted for the entry of and latching engagement with the latch tongue aforesaid.

4. In a safety mechanism for use with the 80 electrical illuminating means of enclosed optical projection apparatus, the combination of an enclosing housing provided with an entry door, a latching head mounted for turning adjustment in the door of a housing and comprising a circular body portion 85 having an operating handle at one end and a flat latch tongue at its other end, said latch tongue having lateral lugs at its free end, and a keeper plate associated with said circuit closing mechanism and having a transverse slit adapted for the entry of and latching engagement with the latch tongue aforesaid.

Signed at Fond du Lac, Wis., this 16th 100 day of November, 1922.

CHARLES LEO FITZ.
